Primary Examiner — Kevin Rudzinski*Assistant Examiner* — John Reickel(74) *Attorney, Agent, or Firm* — Knobbe Martens Olson & Bear LLP**(57) CLAIM**

The ornamental design for a skin clearing and toning device, as shown and described.

DESCRIPTION

FIG. 1 is a perspective view of a skin clearing and toning device of the present invention;

FIG. 2 is a front elevational view of the skin clearing and toning device shown in FIG. 1;

FIG. 3 is a rear elevational view of the skin clearing and toning device shown in FIG. 1;

FIG. 4 is a left side elevational view of the skin clearing and toning device shown in FIG. 1, the right side view being a mirror image of the illustrated view;

FIG. 5 is a top plan view of the skin clearing and toning device shown in FIG. 1; and,

FIG. 6 is a bottom plan view of the skin clearing and toning device shown in FIG. 1.
